A. E. ARMSTRONG.

TRUSS.

APPLICATION FILED OCT. 22, 1920.

1,413,512.

Patented Apr. 18, 1922.

UNITED STATES PATENT OFFICE.

ALBERT EDWARD ARMSTRONG, OF OTTAWA, ONTARIO, CANADA, ASSIGNOR TO JAMES LYMAN ARMSTRONG, OF OTTAWA, ONTARIO, CANADA.

TRUSS.

1,413,512.

Specification of Letters Patent. Patented Apr. 18, 1922.

Application filed October 22, 1920. Serial No. 418,677.

To all whom it may concern:

Be it known that I, ALBERT EDWARD ARMSTRONG, a subject of the King of Great Britain, a resident of the city of Ottawa, Province of Ontario, Dominion of Canada, have invented certain new and useful Improvements in Trusses, of which the following is a specification.

This invention relates to improvements in trusses, and the objects of the invention are to provide a simple and effective means for regulating the pressure of the truss pad.

Further objects of the invention are to generally improve and simplify the construction of the truss and to adapt the working parts to better perform the functions required of them.

It consists essentially of the improved construction hereinafter described in detail in the accompanying specification and drawings.

In the drawings:

Figure 1 is a perspective view of the truss.

Figure 2 is a plan view.

Figure 3 is a cross sectional detail through one of the pads.

Figure 4 is a sectional detail through the spring in the pad when extended.

Figure 5 is a sectional detail of the means for regulating the spring tension on the pad.

Like characters of reference indicate like parts in all the figures.

Referring to the drawings; A and B represent the spring side members of the truss comprising spring wire encased with leather or other material such as is well known in the art having at the end pads C and D adapted to bear against the back of the wearer.

The forward ends of the members A and B being connected by flexible wire E, the end of the member A having a dummy pressure pad F thereon. The whole of the construction now shown being at present well known in the art.

On the wire E, the pressure pad G is mounted by means of a connecting bracket 10 formed with a perforation 11 through which the wire extends, the bracket being held in adjusted position on the wire by set screws 12.

The pad G is formed with a back plate 13 and a recessed spring containing plate 14 of cup-shape extending towards the outer cover

15 of the pad, the space between filled with 55 suitable packing of filling material 16.

17 indicates the spring spiral in form having one end connected to the edge of the member 14 and having the opposite end connected to the pressure rod 18, the opposite 60 end of the pressure rod extending into a recess 19 and a bracket member 11.

The extent to which it extends in the recess is regulated by means of a regulating screw 20 having screw threaded engagement 65 with the open outer end of the recess.

It will be observed that the recess 19 fits closely to the rod 18 at one end and is enlarged and internally screw threaded at the opposite end to receive the regulating 70 screw 20.

It will be seen that the extent of pressure exerted will be regulated by adjusting the screw 20, the further the screw is screwed in, the greater will be the pressure exerted by 75 the rod on the pad G or on any other member of the truss.

As many changes could be made in the above construction and many widely different embodiments of my invention within the 80 scope of the claim constructed without departing from the spirit or scope thereof, it is intended that all matter contained in the accompanying specification and drawings shall be interpreted as illustrative and not 85 in a limiting sense.

What I claim as my invention is:

In a truss, a pressure pad having a rod connected thereto a supporting wire, connecting bracket formed with a perforation 90 through which the wire extends, the said bracket being formed with a recess extending transversely of the perforation and adapted to receive the rod of the pressure pad, the said recess being constricted at one 95 end to fit the pressure rod and being enlarged and internally screw threaded at the opposite end, a regulating screw extending into the screw threaded portion of the recess and adapted to abut the said rod, said screw 100 being adjustable from the exterior of the clothing of the wearer, means for retaining the connecting member in adjusted position on the wire.

In witness whereof I have hereunto set my 105 hand.

ALBERT EDWARD ARMSTRONG.
